ELECTRODE STRUCTURE FOR ELECTRIC
PRECIPITATORS

Hermann Fiesel, deceased, late of Frankfort-on-the-Main, Germany, by Hildegarde A. S. Fiesel, executor, Frankfort-on-the-Main, Germany, assignor to Western Precipitation Corporation, Los Angeles, Calif., a corporation of California

Application December 26, 1939, Serial No. 311,036
In Germany March 26, 1938

7 Claims. (Cl. 183—7)

The present invention is concerned generally with the art of electrically precipitating suspended particles from a stream of gas, and more particularly with improvements in the construction of non-discharging electrodes. The process of precipitating suspended particles from a stream of gas is accomplished by passing the gas stream through an electric charging field in which corona discharge is produced that causes the suspended particles in the gas stream to become electrically charged, and then the charged particles are moved toward and precipitated upon the surface of a non-discharging collecting electrode as a result of the force exerted upon the charge particles by an electric field which may be the charging field just referred to or may be a spatially separate electrostatic field. Apparatus of various types in which these operations are carried out is generally referred to as an electrical precipitator.

In the following description, the term "discharge electrode" will be understood to designate an electrode that facilitates corona discharge therefrom, because it has a configuration that establishes a sufficiently high potential gradient at or near its surface to create a corona discharge before there is a disruptive discharge or sparkover. Conversely, the term "non-discharging electrode" will be understood to designate an electrode that minimizes or prevents corona discharge therefrom because it has a configuration that establishes a sufficiently low field concentration at or near the surface to suppress corona discharge at elevated potentials lower than the voltage required for disruptive discharge or sparkover. For this reason, a non-discharging electrode usually is one of extended surface area that is substantially free from sharp corners or other parts of sharp surface curvature at points within the electric field.

Although in its broad aspect, my invention is not limited to any special material or materials, it is intended particularly to be used with non-metallic semi-conducting materials which may be cast or moulded into elongated, rod-shaped members. One typical application in which the present invention has marked advantages is in the formation of non-discharging electrodes which are made of carbon in order to be resistant to corrosion by acids and other substances. Carbon is a material used particularly in precipitators designed for collection of acid fumes or other fumes which are particularly corrosive. However, it is very difficult and expensive to form carbon into sheets of sufficiently great ex-

tent which are not warped so much as to be unusable. Because of the large amount of material rejected in the manufacture of carbon plates, the cost of acceptable flat sheet material is unusually high.

These disadvantages are overcome according to my invention by building up the non-discharging electrode from a plurality of elongated, rod-shaped members. The rod-shaped members are arranged in layers with the members of each layer spaced from one another and with the members of successive layers laid at an angle, preferably a right angle, with respect to each other. As a result of spacing the members of each layer an equal amount and angularly disposing the members of successive layers, the completed structure of several layers forms one or more polygonal, preferably square, gas passages through which the stream of gas with the suspended particles can pass, each of the gas passages being adapted to receive and surround an opposing electrode which may be either of the discharge or non-discharging type. Ordinarily the layers are horizontal and consequently the gas passages are vertical. Also, the members are advantageously stacked on each other so that each layer supports the layers above it. This construction is simple and economical to erect, as well as being relatively inexpensive from the standpoint of the cost of the materials. However, it is within the scope of my invention to support individually each layer of members.

How the above objects and advantages of my invention, as well as other objects and advantages not specifically mentioned, are attained will be better understood by reference to the following description and the annexed drawing, in which:

Fig. 1 is a fragmentary vertical section through a portion of a typical electrical precipitator illustrating a non-discharging electrode constructed according to my invention;

Fig. 2 is a plan section on line 2—2 of Fig. 1;

Fig. 3 is a fragmentary elevation and section of several rod-shaped members illustrating a modification of the invention in which the members are provided with recesses;

Fig. 4 is a fragmentary elevation of a single one of the members of Fig. 3;

Fig. 5 is a fragmentary elevation and section of several of the rod-shaped members illustrating another modification of the invention in which the members are provided with recesses;

Fig. 6 is a cross-section through the recessed portion of a single member of Fig. 5;

Fig. 7 is a fragmentary perspective view of a

single rod-shaped member of rectangular cross-section; and

Fig. 8 is a fragmentary elevation and section of a hollow rod-shaped member.

5 There is indicated at 10 in Figs. 1 and 2 a vertically extending gas flue or conduit which is rectangular, preferably square, in cross-section. The walls of flue 10 are provided with ledges 10a which support the cribwork structure of the non-
10 discharging electrode indicated generally at 12. The non-discharging electrode 12 is composed of a plurality of rod-shaped members 14 stacked vertically on one another in a series of horizontal layers. The lowermost or bottom layer of members 14 rests directly upon ledges 10a. The layer next above is placed directly upon the bottom layer with the members of one layer disposed at right angles with respect to the members of the other layer. The members of each 15 layer are parallel to one another and spaced from each other, the spacing in all layers preferably being the same as shown in Figs. 1 and 2. By vertically stacking a series of such horizontal layers upon one another as shown in Fig. 1, there 20 results from this arrangement a plurality of vertically extending gas passages or cells 16, as indicated in Fig. 2. Each of these gas passages is a subdivision of the main flue 10 and is adapted to receive and surround a centrally positioned 25 opposing electrode 18, here shown as a discharge electrode comprising a length of wire of relatively small diameter stretched taut by a weight on the lower end of the wire.

Although the opposing electrodes 18 in Figs. 1 35 and 2 are the discharge type, it will be understood that the invention is not limited to any particular type of electrode and that non-discharging electrodes may also be placed within gas passages 16 to oppose electrode 12.

40 Any desired material may be used for the rod-shaped members 14, but it is contemplated that they will be made principally of carbon where a corrosion resistant electrode is desired.

In the cribwork construction illustrated in 45 Figs. 1 and 2, members 14 are solid cylindrical rods. If it is desired to hold the rods against lateral movement, as by rolling, as well as to facilitate vertical alignment of the members 14 in alternate layers, the individual member 14 50 may be recessed in any one of a number of ways. Some typical manners of recessing are illustrated in Figs. 3-7 inclusive; and in general it is preferred to recess the rods at their ends and at the intermediate points where the rods of successive 55 layers cross over or engage each other in order to keep the members 14 in their proper positions and maintain the proper size and shape of the various gas passages 16.

Fig. 3 illustrates one manner of recessing the 60 elongated members 14 in which only the rods of alternate layers, that is the rods 14 viewed in cross-section in Fig. 3, are provided at opposite sides with shallow recesses or notches 20. As shown in Fig. 4, these recesses are diametrically 65 opposite each other and are circular in outline to conform to the periphery of the rods which are to be received in the recesses. Shallow recesses of this type hold the rods in position against lateral displacement such as would occur were 70 the individual members free to roll, and at the same time reduce the spacing between vertically aligned members of alternate layers. Thus in the construction of Fig. 1, the distance between alternate layers is equal to the diameter of the 75 intervening members 14; but in the construction

of Fig. 3 the spacing between alternate layers is reduced by an amount equal to twice the depth of a notch 20.

In the event it is desired to substantially eliminate the spacing between vertically aligned members 14 of alternate layers, this can be accomplished by providing the members with somewhat deeper notches 22 as indicated in Figs. 5 and 6. In this configuration of members 14, recesses 22 are provided in all members both at 10 their ends and also at the intermediate points where the rods of successive layers engage or cross each other, recesses 22 having a depth equal to one-fourth the diameter of the member 14. Two diametrically opposite recesses 22 each 15 of a depth equal to one-fourth the diameter leave a central portion of the member 14 of a thickness of one-half the diameter of the rod, as indicated at 14a in Fig. 6. This portion 14a is received in and fills the space created by two adjoining vertically aligned recesses 22 in the rods of alternate layers, as may be seen from Fig. 5. With this construction, the members 14 of alternate layers, being parallel to one another and vertically aligned, are in contact, or substantially so, throughout their entire length and the spacing between the rods is substantially eliminated. This type of construction not only increases the amount of electrode surface available in the non-discharging electrode 12 to oppose electrode 18, but also somewhat reduces turbulent flow since there is no opening through which the gas may flow from one passage 16 to another.

The construction of Figs. 5 and 6 may be considered as derived from the construction of Figs. 3 and 4 by deepening the recesses and placing recesses in all of the members 14. From this discussion, it will be apparent to those skilled in the art that other sizes and arrangements of recesses may be used. Thus, all members may have recesses as at 22 but of a lesser depth, such as at 20, to hold the members in place but still leave spaces between them.

It is to be understood that the invention is in 45 no way limited to cylindrical rods for members 14, although it is preferred to use members of this shape in building up the electrode since sharp corners tending to produce corona discharge are 50 eliminated. However, under some circumstances it may be entirely satisfactory to use rod-shaped members which are polygonal in outline, or which have a periphery made up of both straight and curved lines. As an example of a different 55 shape of member 14 which may be used, there is illustrated in Fig. 7 a square rod-shaped member 14b which is provided with notches 24 on opposite faces, the notches being rectangular in outline and adapted to receive another square member 14b of the same shape as the one illustrated. 60 When recesses 24 have a depth equal to one-fourth the linear dimension of one side of the square member 14b, the vertically aligned square members of alternate layers rest one upon another and are held in proper alignment to maintain a substantially smooth, unbroken, vertical surface on the inside of each of gas passages 16. The opposing electrode 12 then is much the same as if formed of a continuous sheet at each side of the passages 16, and substantially no detrimental effects are encountered from the presence of the sharp corners on each of the square members 14b. Advantages of square members are 65 that gas flow through the passages 16 is less turbulent, because the walls of the passages are 70 75 80 85 90 95

smoother, and the bearing area of the rods is greatly increased so that larger loads can be carried without crushing.

From the foregoing it will be understood that the term "rod-shaped," as applied to members 14, includes various elongated members characterized by a relatively great longitudinal dimension and relatively small transverse dimensions. The cross-sectional outline may change; and also the members 14 may be hollow as well as solid. By way of example there is shown in Fig. 8 a tubular member 14 with an internal bore 26 extending throughout the length of the member.

Having described my invention and certain preferred embodiments thereof, it will be understood that various changes in the configuration and arrangement of the various parts may be made by those skilled in the art without departing from the spirit and scope of my invention; and consequently it is to be understood the foregoing description is illustrative of, rather than limitative upon, the appended claims.

I claim:

1. A non-discharging electrode structure for use in an electric precipitator, comprising a plurality of cast rod-shaped members made of non-metallic material arranged in layers with the members of each layer spaced from each other and the members of successive layers angularly disposed to each other, and the rod-shaped members being arranged to form a polygonal gas passage adapted to receive and surround an opposing electrode.
2. A non-discharging electrode structure for use in an electric precipitator, comprising a plurality of horizontally extending rod-shaped members stacked vertically on each other in horizontal layers with the members of each layer spaced from each other and the members of successive layers angularly disposed to each other, and the

rod-shaped members being arranged to form a vertically extending polygonal gas passage adapted to receive and surround an opposing electrode.

3. A non-discharging electrode structure for use in an electric precipitator, comprising a plurality of horizontally extending rod-shaped members stacked vertically on each other in horizontal layers with the members of each layer spaced from each other and the members of successive layers disposed at right angles to each other, and the rod-shaped members being arranged to form a vertically extending rectangular gas passage adapted to receive and surround an opposing electrode.

4. A non-discharging electrode structure for use in an electric precipitator, comprising a plurality of rod-shaped members arranged in layers with the members of each layer spaced from each other and the members of successive layers disposed at right angles to each other, and the rod-shaped members being arranged to form a plurality of rectangular gas passages each adapted to receive and surround an opposing electrode.

5. A non-discharging electrode structure as set out in claim 2 in which the members are provided with recesses that engage adjoining members and hold them against lateral displacement.

6. A non-discharging electrode structure as set out in claim 2 in which the members are provided with recesses to engage and hold in place adjoining members and the recesses are of sufficient depth to bring members of alternate layers substantially into contact.

7. A corrosion resistance non-discharging electrode structure as set out in claim 1 in which the rod-shaped members are made principally of carbon.

HILDEGARD A. S. FIESEL,
Executor of the Estate of Herman Fiesel, De-
ceased.
